(57) **CLAIM**

The ornamental design for a spoon, as shown and described.

DESCRIPTION

FIG. 1 is a side elevational view of a spoon showing my new design;

FIG. 2 is a front elevational view of the spoon of FIG. 1;

FIG. 3 is a rear elevational view of the spoon of FIG. 1; FIG. 4 is an end view of the spoon of FIG. 1;

FIG. 5 is an end view of the spoon of FIG. 1 taken in the direction opposite that of FIG. 4;

FIG. 6 is a side elevational view of a second embodiment of a spoon showing my new design;

FIG. 7 is a front elevational view of the spoon of FIG. 6;

FIG. 8 is a rear elevational view of the spoon of FIG. 6;

FIG. 9 is an end view of the spoon of FIG. 6; and,

FIG. 10 is an end view of the spoon of FIG. 6 taken in the direction opposite to that of FIG. 9.
